Inventor:

HARRY ZIMMERMAN

Harry Zimmerman

Attorney

FIG. 1 shows a top view of an illustrative embodiment of my invention, some parts being broken off for the sake of showing the underlying parts.

FIG. 2 shows a partly sectional side view of the same embodiment, the sectionally represented part being cut along the broken line 2-2 in FIG. 1.

FIG. 3 shows a perspective view of a tone bar used in the same embodiment and of a broken off part of the supporting structure, the tone bar being represented in a position higher than the finally assembled position.

FIGS. 4 to 6 show perspective views of three different modifications of the parts shown in FIG. 3, these figures being represented in a manner corresponding to FIG. 3.

FIGS. 1 and 2 are represented on a smaller scale than FIGS. 3 to 6.

Referring to the drawings, numeral 1 indicates a casing which has a top wall or ceiling 3. Tone bars, some of which are indicated by numerals 4 to 7, are supported on the casing 1 at some distance over the top wall 3 in any suitable manner.

Other objects are to facilitate the assemblage of the toy, to reduce the number of parts necessary for the assemblage, and to secure the bars to the supporting structure simply by inserting integral projections of the bars into openings of the casing's top wall.

Further objects are to attain these results with simple and inexpensive means, to provide tone bars of a shape that can be easily made and is adapted for the objects mentioned before, and to provide a musical toy that can be easily and quickly made and assembled, can be easily played and has good sounding quality.

Still other objects and advantages will appear from the following description of exemplifying embodiments of my invention, from the appended claims and from the accompanying drawing in which:

FIG. 1 shows a top view of an illustrative embodiment of my invention, some parts being broken off for the sake of showing the underlying parts.

FIG. 2 shows a partly sectional side view of the same embodiment, the sectionally represented part being cut along the broken line 2-2 in FIG. 1.

FIG. 3 shows a perspective view of a tone bar used in the same embodiment and of a broken off part of the supporting structure, the tone bar being represented in a position higher than the finally assembled position.

FIGS. 4 to 6 show perspective views of three different modifications of the parts shown in FIG. 3, these figures being represented in a manner corresponding to FIG. 3.

FIGS. 1 and 2 are represented on a smaller scale than FIGS. 3 to 6.

Referring to the drawings, numeral 1 indicates a casing which has a top wall or ceiling 3. Tone bars, some of which are indicated by numerals 4 to 7, are supported on the casing 1 at some distance over the top wall 3 in any suitable manner.

FIG. 1 shows the tone bars 4 to 7 which are supported on the top wall 3. The tone bars 4 to 7 are supported on the top wall 3 by strips 9 which are secured to the top wall 3. The tone bars 4 to 7 are supported on the strips 9.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

FIG. 1 shows the tone bars 4 to 7 which are supported on the top wall 3.

FIG. 2 shows the tone bars 4 to 7 which are supported on the top wall 3.

FIG. 3 shows the tone bars 4 to 7 which are supported on the top wall 3.

FIG. 4 shows the tone bars 4 to 7 which are supported on the top wall 3.

FIG. 5 shows the tone bars 4 to 7 which are supported on the top wall 3.

FIG. 6 shows the tone bars 4 to 7 which are supported on the top wall 3.

UNITED STATES PATENT OFFICE

XYLOPHONE

Application October 28, 1948, Serial No. 56,979

14 Claims.

(C1. 84—403)

For example, these bars rest on two strips 9 of soft material which overlie the top wall 3. The strips 3 may be affixed to this wall in any suitable manner, for example, by U-shaped cramps 11 engaging the ends of the strips and being affixed to the top wall. The casing 1 and the strips 9 form the structure supporting the tone bars.

Except for resting on the soft strips, the tone bars are freely movable in all directions whereby their sounding vibrations are unimpaired. Excessive dislocation of the bars, for example, a horizontal shift which would bring one tone bar too close to another tone bar or too far out of line with the other bars, is prevented by restricting or limiting the range of movability of each bar in the manner described hereafter.

Each tone bar has one or preferably two downwardly extending projections which pass through correspondingly located openings of the top wall 3.

An important feature is that these projections are struck out of the material of the bar so that each projection has an upper end coherent with the bar's material and forming an integral continuation of this material. This structure avoids the connection of the projections by riveting, soldering or the like. I have found that tone bars provided with struck out projections have a clearer and better sound effect than bars to which parts are connected by other means. In addition, the manufacture of bars with struck out projections is simpler and less expensive because the projections can be formed together with the bar without any additional operation.

In the embodiment shown in FIGS. 1 to 3, the projections 12 are shaped like hooks having vertical parts 13 passing with clearance through openings 14 of the top wall 3. This structure does not interfere with the vibrations of the bar, but restricts the movability of the bars sufficiently to prevent excessive lateral or horizontal dislocation of the bars.

In addition, means are provided to prevent excessive upward movement of the bars or a vertical dislocation of the same which would bring the projections out of the openings. These restrictive means are constituted by one or several members, each of which is affixed either to a tone bar or to the casing. In the embodiment shown in FIGS. 1 to 3, there are two types of such members, either type or both may be used in one embodiment. One type of vertically restricting members is constituted by an elongated body 15 which extends horizontally at a small distance over the tone bars and is affixed to the casing 1 in any suitable manner. For example, the member 15

may form a bridge having feet 16 affixed on top of the top wall 3. The other type is constituted by the lower ends 17 of the projections 12.

These ends are bent into horizontal direction and extend at a small distance below the top wall 3 when the bar is in assembled condition. Preferably, each tone bar has two projections 12 which may have parts 17 extending horizontally in opposite directions. The lengths of the parts 17 are preferably so measured that, in any position of the bar possible within its range of horizontal movability, at least one of the parts 17 reaches horizontally beyond the respective opening 14. In this case, the projections may be passed through the openings for assemblage while one or both projections are slightly bent oppositely to that direction in which the end 17 reaches beyond the edge of the opening in unbent condition. The projections 12 are sufficiently resilient to allow such a temporary deformation after which they will readily return into the far-reaching or interlocking position.

In the modification illustrated by Fig. 4, tone bars are used which differ from the tone bar shown in Fig. 3 by a different shape of the struck out projections. The bar 21 exemplifies this modification. It has projections 22 which extend downwardly in straight directions and, in assembled position, pass through openings 24 of the top wall with clearance. Also in this case, the lower ends of the projections may reach horizontally beyond the respective openings if the directions of the projections are slightly oblique. The resilience of the projections allows their passage through the openings during the assemblage.

The tone bar 31 shown in Fig. 5 illustrates another modification. The bar 31 has struck out projections 32 which are substantially T-shaped, each comprising a relatively narrow stem 33 extending downwardly and a broader lower end 37 extending horizontally. The corresponding openings 34 of the top wall are slots extending parallel to the lower ends 37 and being longer and wider than the corresponding cross-sections of the stems 33 whereby stems can pass through these openings with clearance. Preferably, the end ends 37 are slightly broader in horizontal direction than the lengths of the slots 34 and are sufficiently resilient to snap through these slots.

The modifications shown in Figs. 3 to 5 are assembled as soon as the tone bars are lowered from the positions shown in these figures until the lower ends of the projections have passed the top wall openings. The further modification illustrated by Fig. 6 is assembled in a slightly different manner. This latter modification comprises a tone bar 41 which has one T-shaped projection 42 with a stem 43 and a broader lower end 47 similar to the projections 32, stem 33 and end 37 described before. The corresponding opening 44 of the top wall forms a slot which is preferably slightly longer and wider than the largest horizontal cross-section of the end 47, but has a direction different from the direction of this end in finally assembled position. For example, the direction of the slot 44 may run at a right angle to the final direction of the end 47 or to the direction of the slot 34 shown in Fig. 5.

Preferably, the bar 41 has an additional projection 45 adapted for passage through an opening 46 of the top wall. The projection 45 may be without broader end and may extend straight downwardly.

The projection 42 is passed through the slot 44 while the bar 41 is turned into the position

shown in Fig. 6. This position is turned about a right angle relatively to the bar's final position. Then the bar is turned in the direction of the arrow 48 until the projection 45 can pass through the opening 46. During this turning movement, the bar may be slightly tilted so that the projection 45 can move over the supporting structure. The resiliency of the projection 45 facilitates this movement and causes the projection 45 to snap into the opening 46. In the position reached in this manner, the long side of the end 47 crosses the direction of the slot 44 whereby the end 47 reaches beyond this slot and the bar is prevented from excessive upward movement.

I desire it understood that my invention is not confined to the particular embodiments shown and described, the same being merely illustrative, and that my invention may be carried out in other ways without departing from the spirit of my invention as it is obvious that the particular embodiments shown and described are only a few of the many that may be employed to attain the objects of my invention.

Having described the nature of my invention, what I claim and desire to protect by Letters Patent is:

1. A xylophone comprising a casing having a top wall with an opening, and a tone bar supported on said casing over said top wall and having a downwardly extending projection passing through said opening and forming a stop for excessive movement of said bar relatively to said casing.

2. A xylophone comprising a casing having a top wall with an opening, and a tone bar supported on said casing over said top wall and having a downwardly extending projection passing with clearance through said opening and forming a stop for excessive lateral movement of said bar relatively to said casing.

3. A xylophone comprising a casing having a top wall with an opening, a tone bar supported on said casing over said top wall and having a downwardly extending projection passing with clearance through said opening whereby said casing and said bar form two elements of which the relative horizontal movability is restricted, and a horizontally extending member affixed to one of said elements in a position where said member restricts the upward movability of said bar relatively to said casing.

4. A xylophone comprising a casing having a top wall with an opening, and a tone bar supported on said casing over said top wall and having a downwardly extending projection struck out of the material of said bar and passing through said opening and forming a stop for excessive movement of said bar relatively to said casing.

5. A xylophone comprising a casing having a top wall with an opening, and a tone bar supported on said casing over said top wall and having a downwardly extending projection passing through said opening and forming a stop for excessive movement of said bar relatively to said casing, the lower end of said projection being lower than said top wall and extending, in horizontal direction, beyond said opening whereby the upward movability of said bar is restricted.

6. A xylophone comprising a casing having a top wall with two openings, a tone bar supported on said casing over said top wall and having two downwardly extending projections passing with clearance through said openings whereby the

horizontal movability of said bar is restricted, one of said projections having a lower end positioned lower than said top wall and, in horizontal direction, extending so far that this end reaches beyond the opening passed by said latter projection in each of the restricted positions of said bar.

7. A xylophone comprising a casing having a top wall with two openings, a tone bar supported on said casing over said top wall and having two downwardly extending projections passing with clearance through said openings whereby the horizontal movability of said bar is restricted, said projections having lower ends positioned lower than said top wall and horizontally extending in opposite directions so far that each of said ends reaches beyond the opening passed by the respective projection, at least one of said projections being sufficiently resilient to allow resilient withdrawal of its far reaching end whereby said projections can be inserted in said openings.

8. A xylophone comprising a casing having a top wall with an opening, and a tone bar supported on said casing over said top wall and having a downwardly extending projection which has a part passing with clearance through said opening and has a part positioned below said opening and being slightly broader than said opening, said broader part being sufficiently resilient to be snapped through said opening.

9. A xylophone comprising a casing having a top wall with a slot, and a tone bar supported on said casing over said top wall and having a downwardly extending projection which has a part passing through said slot with clearance and has a part positioned below said slot, being horizontally broader than the width of said slot but not broader than the length of said slot whereby said latter part can pass through said slot when positioned with its broad side along said slot and can then be turned into a position where its broad side crosses the direction of said slot.

10. A tone bar for a xylophone having a horizontally extending main part, and a projection extending downwardly from said main part in

substantially perpendicular direction thereto and being adapted to serve as a stop for excessive movement of the bar.

11. A tone bar for a xylophone having a horizontally extending main part, and a projection struck out of the material of said main part, extending downwardly from said main part in substantially perpendicular direction thereto and being adapted to serve as a stop for excessive movement of the bar.

12. A tone bar for a xylophone having a horizontally extending main part, and a projection which has a part extending downwardly from said main part and has a part forming a continuation of said downwardly extending part and extending horizontally at some distance from said main part.

13. A xylophone comprising a frame having a top wall provided with an opening, and a tone-bar supported on said frame and having a downwardly extending projection passing through said opening, and means for preventing excessive movement of the bar relatively to said frame.

14. A xylophone comprising a casing having a top wall with an opening and a tone bar supported on said casing over said top wall and having a downwardly extending projection which has a part passing with clearance through said opening and has a part positioned below said opening and being at least as broad as said opening, but sufficiently narrow to allow said latter part to be forced through said opening when said projection is inserted in said opening.

HARRY ZIMMERMAN.
